CLAIM

We claim the ornamental design for a coagulometer, as shown and described.

DESCRIPTION

FIG. 1 is a top, front perspective view of a coagulometer showing our new design with the test strip door in the closed position;

FIG. 2 is a bottom, rear perspective view thereof;

FIG. 3 is a front view thereof;

FIG. 4 is a right side view thereof;

FIG. 5 is a rear view thereof;

FIG. 6 is a left side view thereof;

FIG. 7 is a top view thereof; and,

FIG. 8 is a bottom view thereof.

The shade lines show transparency, not surface ornamentation.

The broken lines depict portions of the coagulometer that form no part of the claimed design.
